OSCAR E. GROSELL, OF SALT LAKE CITY, UTAH.

REMOTE CONTROL FOR INDICATORS.

Application filed January 21, 1920. Serial No. 353,104.

To all whom it may concern:

Be it known that I, OSCAR E. GROSELL, a citizen of the United States, and a resident of Salt Lake City, in the county of Salt Lake and State of Utah, have invented certain new and useful Improvements in Remote Controls for Indicators, of which the following is a specification.

My invention relates to improvements in indicators, it relating more particularly in the means whereby such indicators are capable of control from a remote point, and it consists in the constructions, combinations and arrangements herein described and claimed.

The foremost object of my invention is to provide electrical switch mechanism to be operatively associated with any type of indicator, as for example, such as described in my co-pending application filed Jan. 21, 1920, Serial No. 343,105, and capable of being controlled or operated from a remote point.

Other objects and advantages will appear in the following specification, reference being had to the accompanying drawing, in which:—

Figure 1 is a plan view of the improved remote control, and

Figure 2 is a side elevation thereof, certain of the circuits which cooperate therewith, being illustrated diagrammatically.

In order that the manner in which the invention is associated with a cash register, for example, and an auxiliary indicator therefor, may be understood, it is necessary to first briefly describe a portion of the cash register, and then that portion of the auxiliary indicator with which the remote control is directly associated.

The cash register contains a plurality of rows of keys respectively constituting the "units," "tens," "hundreds," etc., columns, each row of keys being numbered from "1" to "9." This is a common and well known arrangement. For the purpose of illustration, one of the keys, designated 24, is shown in Figure 2.

The shank 25 of this key is arranged to engage a contact 41 when the key is depressed. The key when thus depressed, remains so until it is released by mechanism which forms a part of the cash register. The contact 41 is mounted on an insulating strip 40. The adjacent metallic part of the cash regis-

ter frame is indicated 49. This frame constitutes a ground connection, to which a wire 51 from a movable contact 27 leads. This contact cooperates with a fixed contact 26.

The auxiliary cash register indicator comprises a plurality of drop magnets, one of which is designated 9^a in Figure 2. There is one drop magnet for each key of the cash register. Contact points at two places are required to be engaged before the circuit embracing the drop magnet 9^a, is completed.

One of these contact points occurs between the shank 25 of the key 24 and the contact 41 with which the shank cooperates, and the other occurs at the main drop switch 35. This switch comprises a solenoid 30, to the core 31 of which, the actuator shaft 32 is joined. This shaft carries the contact 33 to engage the fixed contact 34 when the core 31 is drawn in by virtue of the energization of the solenoid.

Both the drop magnets 9^a and the main drop switch 35, with its companion mechanism, are parts of the auxiliary indicator which are controlled by the switch mechanism which forms the basis of this application. By virtue of the fact that this switch mechanism is arranged to be actuated from a distant point, it is herein termed a remote control.

A wire 45 leads from the positive terminal of the secondary of the transformer 46, to one of the fixed contacts 34 of the main drop switch 35. A branch of this same wire also connects to the release magnet 28, which is a part of the remote control and is more fully described below. A wire 47 leads from the other contact 34 to the drop magnet 9^a. A wire 42 leads from the other end of the winding of the drop magnet to the contact 41 of the cash register. A wire 48 leads from the negative terminal of the secondary of the transformer to the ground connection or frame 49 of the cash register.

Wires 77 and 78 lead to the primary of the transformer 46. A branch 77^a of the wire 77, connects to one end of the winding of the solenoid 30, while a branch 78^a of the wire 78 leads through the plate 75 of the remote control switch, which is now described. The release magnet 28, mentioned above, is suitably mounted on one side of a plate 56, which is made of metal. Upon the attraction of the armature 52 by the energization of the magnet 28, the latch disk 53,

by which the armature is carried, is partially rotated, causing the lifting of the latch 54 from engagement with the end of the arm 55. The latch 54 is carried by the disk 53, 5 and extends through a suitable opening in the plate 56 on which the disk is pivotally mounted at 57.

A pin 58 carried by a normally raised locking pawl 59, causes the movement of the locking pawl into the dotted line position in Figure 2, by virtue of the connection of the pin with the latch disk 53 on back of the plate 56. Therefore, although the arm 55 is released by the latch 54, it is immediately 10 caught and again held by the locking pawl 59 until the release magnet 28 is deenergized. All this takes but an instant and the arm 55 is again released so that it may continue to move and reach the dotted line position.

20 A spring 60 causes the arm 55 to move into this position. The arm carries a switch disk 61, of insulating material, and this disk moves with the arm. Both are pivoted at 62. The disk has an opening 63 through 25 which the pivot screw 64 of the switch arm 65 can be reached. A spring 66 joins the extension of the switch arm 65 to the lock stud 67 on the disk 61. Normally, the spring 66 holds the contact 68 of the switch arm 65 in 30 engagement with the light contact 69 on an insulating plate 70. A lamp 71 is suitably connected to the contact 69 and branch 77^a, so that when the switch arm 65 is in the normal position, shown in full lines, the lamp is 35 lighted. On the other hand, when the switch arm 65 is raised, the lamp is extinguished.

Pivoted at 82 to the lower end of the latch arm 55, is a return arm 81. This arm has a slot 83 which is occupied by the pin 84 on the 40 adjustable collar 85 of the actuator shaft 32. The actuator shaft shown in connection with the switch mechanism in Figure 2, is the same actuator shaft that is shown diagrammatically on the lower part of the sheet. 45 The reader will understand that this duplication is necessary in order to make it clear how the circuit connections run and also to show how the return arm is connected to the same actuator shaft. Actually in the machine, there is only one actuator shaft.

50 Cooperating with the contact 68 of the switch arm 65, is a fixed contact 79 which has a wire 80 leading to the other end of the winding of the solenoid 30. As more fully described below, the switch arm 65 is arranged to be moved into the dotted line position, whereupon the contacts 68 and 79 engage to complete a circuit through the solenoid. In order that this contact may be 55 maintained for a relatively great length of time, the switch arm 65 is provided with a holding stud 88, arranged to enter the aperture 87 of the spring lock plate 86.

The lock stud is released from the aperture 87 when the stud 67, to which one end

of the spring 66 is connected, moves beneath the portion 89 of the spring lock 86, springing it outwardly and thereby releasing the switch arm.

The operation.

70

Assume that the operator wishes to record a sale involving the use of the key "9". He depresses the key. The shank 25 engages the contact 41 and thus closes one part of the 75 circuit embracing the drop magnet 9^a. A movable part of the cash register, as for example, a pivoted handle, is subsequently operated so that the contacts 26, 27 are brought into engagement, causing current to flow as 80 follows:

From the positive terminal of the secondary of the transformer 46, over wire 45, through release magnet 28, to contact 26, through contact 27, over wire 51 to ground 85 49, and back to the negative terminal of the secondary of the transformer over the wire 48. The energization of the magnet 28 attracts the armature 52. The latch disk 53 is partially rotated in a counterclockwise 90 direction, releasing the latch arm 55 which moves but a short distance, however, because of the fact that the same rotation of the latch disk 53 causes the lowering of the locking pawl 59 into the path of the arm 55. 95

The contact at 26 and 27 is but instantaneous, consequently the magnet 28 is again deenergized almost immediately. This causes the counter-rotation of the latch disk 53 and the consequent raising of the locking pawl 59. The switch disk 61 therefore moves into the dotted line position by virtue of the spring 66. As soon as the stud 67 gets below the horizontal center on which the pivot 64 is located, the spring 66 will operate to 105 move the switch arm 65 into the dotted line position, so that a circuit is completed as follows:

Current flows from the line wire 78, over branch 78^a to the plate 75, through the 110 switch arm 65, to contact 79, over wire 80 through the winding of the solenoid 30, and over branch 77^a back to the negative line wire 77. The solenoid thus being energized, draws the core 31 in and causes the contact 115 33, 34 of the switch 35 to engage. The second point of the circuit embracing the drop magnet 9^a is then closed and consequently current flows as follows:

From the positive terminal of the secondary of the transformer 46 over wire 45 through the contact 33, 34, over wire 47 through the winding of the drop magnet 9^a, over wire 42 to contact 41, shank 25, ground 49, and over the return wire 48 to the negative terminal of the secondary of the transformer. The energization of the drop magnet 9^a causes the dropping of a corresponding plate which forms a part of the auxiliary indicator and requires no illustration here, 130

since it is illustrated in the co-pending application above referred to.

Reverting for a moment to the time when the disk 61 is moved to the dotted line position, it is to be observed that the return arm 81 also moved to the dotted line position so that the base of the slot 83 approached the pin 84 on the collar 85. In the same movement, the switch arm 65 became locked into the contact engaging position, shown in dotted lines, by virtue of the engagement of the stud 88 in the aperture 87 of the lock plate 86.

Returning now to the moment of energization of the solenoid 30. The attraction of the core 31 causes the actuator shaft 32 to move toward the left so that the pin 84 engages the return arm 81 at the base of the slot 83, and causes the arm 55, together with the disk 61 on which it is mounted, to return to the normal position. Were it not for the engagement of the stud 88 with the aperture 87, the switch arm 65 would fly back to the full line position as soon as the stud 57 reached a point above the horizontal center on which the pivot 64 is located.

This is positively prevented, and must necessarily be so, because in the operation of the auxiliary indicator the actuator shaft 32 is required to make substantially a full stroke in order to return certain indicator plates, before the contacts 33, 34 are brought into engagement. Consequently, the disk 61 is permitted to reach substantially the normal full line position before the contacts 68, 79 are broken, thus allowing for the engagement of the contacts 33, 34 and the energization of the drop magnet 9^a. Now as soon as the stud 67 rides beneath the portion 89, the spring lock 86 is raised, releasing the stud 88 and permitting the switch arm 65 to fly back by virtue of the spring 66. When the contact 68 engages the contact 69, the lamp 71 is lighted, and thus a cycle of operation is completed. It is to be observed that the actuator shaft 32 is returned to the normal extended position by a spring 116 which moves the shaft toward the right.

While the construction and arrangement of the remote control switch as herein described and claimed, is that of a generally preferred form, obviously modifications and changes can be made without departing from the spirit of the invention or the scope

55 of the claims.

I claim:—

1. A remote control for indicators, comprising electro-magnetic release means controlled from a remote point, shiftable switch control means, means under control of said electro-magnetic means for governing the shifting of said control means, and a switch member operatively associated to be rocked upon the shifting of said switch control

60 means. 2. A remote control for indicators, comprising electro-magnetic release means controlled from a remote point, shiftable switch control means, means under control of said electro-magnetic means for governing the shifting of said switch control means, and means for holding said switch member when rocked to the operative position.

3. A remote control for indicators, comprising electro-magnetic release means controlled from a remote point, shiftable switch control means, means under control of said electro-magnetic means for governing the shifting of said control means, a switch member operatively associated to be rocked upon the shifting of said switch control means, means for holding said switch member when rocked to the operative position, and means carried by said control means, for releasing said switch member from said holding means, on the return movement of said control means.

4. A remote control for auxiliary cash register indicators, electro-magnetic release means controlled from a remote point, latch means and latch actuating means arranged to be rocked when the electro-magnetic means is energized, and having operative connection to said latch to shift the latter.

5. Switch mechanism, comprising an electro-magnet, a normally raised locking pawl, a latch disk with an armature capable of attraction by the electro-magnet to rock said disk, and connecting means between the disk and pawl, to lower the pawl when the disk is rocked.

6. The combination, of a latch disk, electro-magnetically rocked in one direction and mechanically rocked in the return direction; and a pivoted latch, with connecting means for moving the latch in accordance with the rocking of said disk.

7. Switch mechanism, comprising a pivotally mounted switch arm, controlling means therefor, including a shiftable disk, connecting means between the disk and the arm causing the arm to rock to an operative position after the disk has shifted a predetermined distance, and operatively associated means for holding the arm in said position in opposition to the restoring influence of said connecting means on the return shifting of said disk, until said disk reaches approximately the original position.

8. Switch mechanism, comprising a pivotally mounted switch arm, a shiftable switch control disk, resilient connecting means between the disk and the arm to rock the arm to an operative position after a predetermined shifting of the disk, locking means for holding the switch arm in said position in opposition to the restoring effort of said resilient connection on the return movement of the control disk, and means operatively associated with the disk for automatically

115

120

125

130

actuating said locking means to release said arm when the disk reaches substantially the normal position.

9. Switch mechanism, comprising a pivotally mounted switch arm, a shiftable switch control disk, resilient means connecting the disk to an extension of the arm to rock the arm to an operative position after a predetermined shifting of said disk, resilient lock means for catching a portion of the arm and holding said arm in the operative position against the influence of said resilient connecting means on the return movement of said disk, and unlocking means including a stud, carried by the control disk for engaging said resilient lock means and automatically release said switch arm when the disk reaches approximately the original position.

10. Switch mechanism, comprising a pivotally mounted switch arm, a shiftable disk, with a resilient connection to said arm, to rock the arm to an operative position after a predetermined shifting of the disk, operatively associated means for shifting the disk, electrically controlled latch mechanism normally holding the disk but enabling shifting thereof upon energization, and means for holding the switch arm in the operative position in opposition to the restoring effort of the aforesaid connection, until the disk approximately reaches the normal position on the return movement.

11. The combination, of a shiftable switch arm control disk with a latch arm, a latch disk with a latch normally engaging said arm, a normally raised locking pawl in operative connection with said disk, and electro-magnetic means for rocking the disk to release the latch arm and lower the locking pawl into the path of said arm.

12. The combination, of a shiftable switch arm control disk with a latch arm, a latch disk with a latch normally engaging said arm, a normally raised locking pawl in operative connection with said disk, electro-magnetic means for rocking the disk to release the latch arm and lower the locking pawl into the path of said arm, and means for shifting the disk to another position

when the latch arm is released by said pawl on the subsequent deenergization of said electro-magnetic means.

13. Switch mechanism, comprising a pivotally mounted switch arm, with operatively associated contacts and a solenoid arranged to be energized by said arm; a shiftable disk, having a resilient connection to said arm to shift the switch arm into operative position after a predetermined movement of said disk; a latch arm carried by the disk, a pivotally mounted latch disk with a latch normally engaging said arm, resilient operating means associated with said disk, a locking pawl, with an operative connection to the latch disk whereby the pawl is normally held raised; an electro-magnet remotely controlled to rock the latch disk, release the latch arm and move the pawl into the path of said arm, said pawl again raising to release the arm upon deenergization of said electro-magnet; means for holding the switch arm in the operative position, means operatively associated with the latch arm and a portion of said solenoid to return the shiftable disk when the solenoid is deenergized, and means carried by said disk for releasing the switch arm when the disk approximately reaches the normal position.

14. The combination, of a shiftable control disk with an opening, a switch arm pivotally mounted behind a disk, and a resilient element connecting the disk to an extension of the arm and joining said arm through said opening.

15. The combination, of a shiftable control disk having an opening, a switch arm pivotally mounted behind the disk, a resilient connection in front of the disk, joining an extension of said arm through said opening, and being arranged to rock the switch arm to an operative position upon shifting of the disk a predetermined distance; and lock means depending in front of the disk, for catching and holding a portion of the switch arm, said lock means including a portion engageable by said disk on the return movement to again release the switch arm.

OSCAR E. GROSELL.
